SOLE FOR FOOTWEAR

Damon G. Meadows, Bel Air, Md., assignor to Bata Shoe Company, Inc., a corporation of New York

Filed Feb. 8, 1968, Ser. No. 10,511

Term of patent 14 years

U.S. Cl. D2—320
Int. Cl. D2—04

I claim:

The ornamental design for a sole for footwear, as shown.
